Patented June 2, 1959

185,406

CAP FOR A CLOTHESLINE POLE

Frank J. Wesolowski, New Berlin, Wis.

Application January 27, 1958, Serial No. 49,418

Term of patent 7 years

(Cl. D49—1)

Fig. 1

Fig. 2

Fig. 3

Fig. 1 is a perspective view of a cap embodying my new design;

Fig. 2 is an elevational view of the cap shown in Fig. 1; and

Fig. 3 is a plan view of the cap shown in the other figures.

I claim:

The ornamental design for a cap for a clothesline pole, substantially as shown.
